ESTERS OF 16,17-[3',1'-(3'-CARBOXY-2'-PYRAZO-LINO)]PREGNEN-20-ONES AND METHODS FOR THEIR PREPARATION

George P. Mueller, Park Ridge, Ill., assignor to G. D. Searle & Co., Chicago, Ill., a corporation of Illinois

No Drawing. Application April 20, 1953, Serial No. 349,984

6 Claims. (Cl. 260—239.5)

The present invention relates to a new group of esters of pentacyclic pyrazolinocarboxylic acids and, more particularly, to esters of 16,17-[3',1'-(3'-carboxy-2'-pyrazolino)]pregnen-20-ones containing an oxygen atom attached to the carbon atom in position 3 of ring A.

The compounds which constitute this invention can be represented by the structural formula

wherein R is a member of the class consisting of lower alkyl and di-(lower)alkylamino-(lower)alkyl radicals, =X is a member of the class consisting of

and

radicals and wherein one unsaturated carbon to carbon linkage is attached to carbon-5 of the steroid nucleus. The location of the double bond in the pyrazoline nucleus is not established with certainty and, while the ultraviolet spectra favor the formula shown above, it is nevertheless possible that the formula should be drawn as

In the foregoing structural formulas, R can represent a lower alkyl radical such as methyl, ethyl, straight and branched chain propyl, butyl and hexyl. R can also represent a di-(lower)alkylamino-(lower)alkyl radical of the type

-Alk-N(lower alkyl)2

wherein the lower alkyl groups are of the type mentioned above the Alk is a lower alkylene radical such as ethylene, propylene, butylene, trimethylene, tetramethylene, pentamethylene and hexamethylene. The radical =X, at-

2

tached to carbon-3 of the steroid moiety, can be an oxo,

or a

wherein the lower alkyl group is of the type mentioned above.

The compounds of my invention can be prepared by reaction of a 3-oxygenated 16-dehydropregn-20-one of the type

with an excess of a diazoacetate.

This reaction provides valuable hormonal and cardiovascular agents with a normalizing effect on irregular heart action. The claimed esters can be hydrolyzed to the free 3'-carboxylic acids. The latter serve as starting materials in the preparation of other esters and amides, and particularly of dialkylaminoalkylamides. Especially valuable hormonal and cardiovascular agents are obtained when the claimed esters are subjected to the pyrolytic reaction

which yields the esters of the 3-oxygenated 16,17-carboxy-methylenepregn-20-ones.

The following examples describe in further detail certain of the compounds which constitute this invention and methods for their preparation. However, the invention should not be construed as limited thereby in spirit or in scope. It will be obvious to chemists skilled in the art that numerous modifications in methods and materials may be adopted without departing from the scope of the invention. In these examples, quantities are indicated in parts by weight and temperatures in degrees centigrade.

EXAMPLE 1

Ethyl ester of 3-acetoxy-16,17-[3',1'-(3'-carboxy-2'-pyrazolino)]-Δ5-pregnen-20-one

A mixture of 71 parts of 3-acetoxy-Δ5,16-pregnadien-20-one and 103 parts of ethyl diazoacetate is heated on an oil bath at 115-120° C. for 75 minutes. There is an evolution of gas and the crystal cake melts slowly. On cooling a crystalline cake forms again. Successive recrystallizations from benzene and from methanol yield the ethyl ester of 3-acetoxy-16,17-[3',1'-(3'-carboxy-2'-pyrazolino)]-Δ5-pregnen-20-one, melting at about 217-222°

C. with decomposition. The compound has the structural formula

EXAMPLE 2

Ethyl ester of 3-acetoxy-16,17-carboxymethylene-Δ⁵-pregn-20-one

40 parts of the ethyl ester of 3-acetoxy-16,17-[3',1'-(3'-carboxy-2'-pyrazolino)]-Δ⁵-pregn-20-one are mixed with boiling stones and heated under nitrogen for 10 minutes at 230-240° C. After cessation of the evolution of nitrogen, the product is cooled and taken up in 2800 parts of ether. The resulting solution is concentrated to one-half of its original volume and chilled to yield the ethyl ester of 3-acetoxy-16,17-carboxymethylene-Δ⁵-pregn-20-one in the form of long, flat needles. Upon recrystallization from ether, needles are obtained melting at 225.5-226.5° C. This product presumably consists of the 16α-isomer. A dioxane solution shows a specific rotation $[\alpha]_D = -34^\circ$.

The etheric mother liquors are concentrated and a benzene solution of the residue is applied to a silica gel chromatography column. Elution with a 5% solution of ethyl acetate in benzene yields first an additional quantity of material melting at about 225.3-226.5° C. and then a substance which, recrystallized from ethyl acetate, melts at about 201-203° C., consisting presumably of the 16α-isomer of the ethyl ester of 3-acetoxy-16,17-carboxymethylene-Δ⁵-pregn-20-one. The specific optical rotation of a dioxane solution of this product is $[\alpha]_D = -17^\circ$. The ethyl ester of 3-acetoxy-16,17-carboxymethylene-Δ⁵-pregn-20-one has the structural formula

EXAMPLE 3

16,17-[3',1'-(3'-carboxy-2'-pyrazolino)]-Δ⁵-pregn-20-one

A solution of 25 parts of potassium hydroxide in 50 parts of water and 40 parts of methanol is refluxed with a solution of 5 parts of the ethyl ester of 3-acetoxy-16,17-[3',1'-(3'-carboxy-2'-pyrazolino)]-Δ⁵-pregn-20-one in 800 parts of methanol for one hour under nitrogen. Then 400 parts of water are added and the mixture is chilled. A sufficient amount of dilute hydrochloric acid is added to the filtrate to lower the pH to about 4. The resulting solution is partially concentrated in vacuo. The precipitate is collected on a filter. The 16,17-[3',1'-(3'-carboxy-2'-pyrazolino)]-Δ⁵-pregn-20-one melts at about 241-244° C.

EXAMPLE 4

Ethyl ester of 16,17-[3',1'-(3'-carboxy-2'-pyrazolino)]-Δ⁵-pregn-3-ol-20-one

A mixture of 31.4 parts of Δ⁵,16-pregnadien-3-ol-20-one

and 25 parts of ethyl diazoacetate is heated under reflux at 120-140° C. for one hour. Upon cooling a brown oil is obtained. The ethyl ester of 16,17-[3',1'-(3'-carboxy-2'-pyrazolino)]-Δ⁵-pregn-3-ol-20-one shows ultraviolet absorption maxima at 290 and 317 millimicrons and infrared maxima at 2.92, 6.38 and 8.91 microns. It has the structural formula

EXAMPLE 5

16,17-carboxymethylene-Δ⁵-pregn-3-ol-20-one

23 A solution of 4 parts of the 3-acetoxy-16,17-carboxymethylene-Δ⁵-pregn-20-one in 360 parts of methanol is treated with a solution of 20 parts of potassium hydroxide in 50 parts of water and 40 parts of methanol. After standing for 12 hours the mixture is treated with 2000 parts of water and then with a sufficient amount of dilute hydrochloric acid to lower the pH to 4. The reaction mixture is extracted with ether and the ether extract is dried over anhydrous sodium sulfate, filtered and evaporated to yield the 16,17-carboxymethylene-Δ⁵-pregn-3-ol-20-one, which is crystallized from methanol and then from ethyl acetate. The very fine needles melt at about 297-302° C.

EXAMPLE 6

40 *Methyl ester of 16,17-[3',1'-(3'-carboxy-2'-pyrazolino)]-Δ⁵-pregn-3-ol-20-one*

45 A mixture of 30 parts of Δ⁵,16-pregnadien-3-ol-20-one and 21 parts of methyl diazoacetate is heated under reflux at 120-140° C. for an hour. Upon cooling the methyl ester of 16,17-[3',1'-(3'-carboxy-2'-pyrazolino)]-Δ⁵-pregn-3-ol-20-one is obtained which has the structural formula

50 55 60 65 60 parts of this compound are mixed with boiling stones and heated for 15 minutes at about 225° C. under nitrogen. When the nitrogen development ceases, the product is cooled and dissolved in ether. The solution is washed with water, dried over sodium sulfate, filtered and concentrated to yield the methyl ester of 16,17-carboxymethylene-Δ⁵-pregn-3-ol-20-one, which melts at about 235-236° C.

70 75 The same ester is obtained by treatment of a solution of 3 parts of 16,17-carboxymethylene-Δ⁵-pregn-3-ol-20-one in 7000 parts of ether with an etheric solution of diazomethane prepared from 4 parts of nitrosomethylurea. Excess acetic acid is added and the ether solution is washed with water, saturated sodium bicarbonate, water

and sodium chloride, dried over sodium sulfate and concentrated in vacuo until crystallization occurs. The precipitate is collected on a filter and washed with ether. The elongate crystals melt at 235.8-237.2° C.

EXAMPLE 7

3-acetoxy-16,17-[3',1'-(3'-carboxy-2'-pyrazolino)]- Δ^5 -pregnen-20-one

One part of 16,17-[3',1'-(3'-carboxy-2'-pyrazolino)]- Δ^5 -pregnen-3-ol-20-one is treated with 20 parts of acetic anhydride and 20 parts of pyridine at room temperature for 20 hours and then poured on ice and water. The mixture is extracted with ether and the ether extract is washed with dilute hydrochloric acid and water, dried over anhydrous sodium sulfate and evaporated. Crystallization from benzene and petroleum ether yields the 3-acetoxy-16,17-[3',1'-(3'-carboxy-2'-pyrazolino)]- Δ^5 -pregnen-20-one in crystals melting at 233.0-233.6° C. The specific optical rotation of a dioxane solution is $[\alpha]_D = +209.5^\circ$. The ultraviolet absorption spectrum shows a maximum at 272 millimicrons with a molecular extinction coefficient of 8408.

EXAMPLE 8

 β -Dimethylaminoethyl ester of 3-acetoxy-16,17-[3',1'-(3'-carboxy-2'-pyrazolino)]- Δ^5 -pregnen-20-one

A solution of 5 parts of the ethyl ester of 3-acetoxy-16,17-[3',1'-(3'-carboxy-2'-pyrazolino)]- Δ^5 -pregnen-20-one in 30 parts of dimethylaminoethanol is brought to boiling and treated with a small amount of sodium. The slightly yellow solution is refluxed for 15 minutes and then cooled. The unreacted dimethylaminoethanol is removed by vacuum distillation and the residue is dissolved in 50 parts of glacial acetic acid. This solution is poured into excess sodium bicarbonate solution. The latter is extracted with ether and the extract is washed with water and aqueous sodium chloride solution and dried over sodium sulfate; it is then filtered and evaporated. The residue is crystallized first from a mixture of acetone and petroleum ether and then from acetone with charcoal decolorization. The β -dimethylaminoethyl ester of 3-acetoxy-16,17-[3',1'-(3'-carboxy-2'-pyrazolino)]- Δ^5 -pregnen-20-one melts at about 167.5-170° C. The specific optical rotation of a dioxane solution is $[\alpha]_D = +175.9^\circ$. The ultraviolet absorption spectrum shows maxima at 290 and 317 millimicrons with molecular extinction coefficients of 8100 and 7300 respectively. The compound has the structural formula

EXAMPLE 9

 β -Dimethylaminoethyl ester of 16,17-[3',1'-(3'-carboxy-2'-pyrazolino)]- Δ^5 -pregnen-3-ol-20-one

A mixture of 12 parts of 16,17-[3',1'-(3'-carboxy-2'-pyrazolino)]- Δ^5 -pregnen-3-ol-20-one in 270 parts of isopropanol and 70 parts of β -chloroethyldiethylamine is refluxed for 4 hours, cooled and diluted with water. The solution is rendered alkaline by addition of dilute sodium bicarbonate solution and extracted with ether. This extract is dried over sodium sulfate, filtered and concentrated to yield the β -diethylaminoethyl ester of 16,17-[3',1'-(3'-carboxy-2'-pyrazolino)]- Δ^5 -pregnen-3-ol-20-one

70

75

in the form of needles which melt at about 93-95° C. The compound has the structural formula

EXAMPLE 10

 β -Diethylaminoethyl ester of 16,17-carboxymethylene- Δ^5 -pregnen-20-one

A solution of 6 parts of 16,17-carboxymethylene- Δ^5 -pregnen-3-ol-20-one in 270 parts of isopropanol is refluxed for 4 hours with 2.7 parts of β -chloroethyldiethylamine. The reaction mixture is then cooled, diluted with 3 volumes of water, made alkaline with aqueous sodium bicarbonate solution and extracted with ether. The extract is dried over calcium sulfate, filtered and concentrated to yield the β -diethylaminoethyl ester of 16,17-carboxymethylene- Δ^5 -pregnen-20-one in heavy needles, which melt at about 151-153° C.

EXAMPLE 11

Ethyl ester of 16,17-[3',1'-(3'-carboxy-2'-pyrazolino)]- Δ^4 -pregnene-3,17-dione

A mixture of 31.2 parts of 16-dehydroprogesterone and 25 parts of ethyl diazoacetate is heated at 125° C. for an hour and the resulting gummy product is taken up in 1400 parts of hot ether. The ether solution is evaporated to yield the ethyl ester of 16,17-[3',1'-(3'-carboxy-2'-pyrazolino)]- Δ^4 -pregnene-3,17-dione as a yellow oil. The compound has the structural formula

EXAMPLE 12

Methyl ester of 16,17-[3',1'-(3'-carboxy-2'-pyrazolino)]- Δ^4 -pregnene-3,17-dione

Heating of 30 parts of 16-dehydroprogesterone and 21 parts of methyl diazoacetate yields the methyl ester of 16,17-[3',1'-(3'-carboxy-2'-pyrazolino)]- Δ^4 -pregnene-3,17-dione which is isolated in the manner described in the preceding example. This ester is heated under nitrogen for 15 minutes at 225° C. After cessation of the nitrogen development, the product is cooled and dissolved in ether. Concentration yields the methyl ester of 16,17-carboxymethylene- Δ^4 -pregnene-3,17-dione. The same ester is obtained by the following procedure. In a nitrogen atmosphere a solution of 1.9 parts of the methyl ester of 16,17-carboxymethylene- Δ^4 -pregnene-3-ol-20-one in 135 parts of toluene is treated with 3 parts of aluminum isopropoxide in 15 parts of toluene and with 10 parts of cyclohexanone. After refluxing gently for an hour, the mixture is treated with 20 parts of a saturated aqueous Rochelle salt solution and then steam distilled for an hour. The residue is extracted with ether and the extract is washed with water, dried over sodium sulfate, filtered and evaporated to yield the methyl ester

of 16,17-carboxymethylene- Δ^4 -pregnene-3,17-dione in crystals melting at 203-204° C.

I claim:

1. A member of the class consisting of the compounds of the structural formulas

and

wherein X is a member of the class consisting of hydrogen and (lower alkyl)-CO-radicals and R is a member of the class consisting of lower alkyl radicals and radicals of the structural formula (lower alkyl)₂-N-(lower alkylene).

2. A compound of the structural formula

3. A compound of the structural formula

wherein Alk is a lower alkylene radical.

4. A compound of the structural formula

5. A compound of the structural formula

wherein Alk is a lower alkylene radical.

6. A compound of the structural formula
